UNITED STATES PATENT OFFICE.

CHARLES SEIDMAN, OF PHILADELPHIA, PENNSYLVANIA.

NECKTIE FABRIC.

Application filed September 27, 1923. Serial No. 665,077.

To all whom it may concern:

Be it known that I, CHARLES SEIDMAN, a citizen of the United States, residing at Philadelphia, county of Philadelphia, State 5 of Pennsylvania, have invented a new and useful Necktie Fabric, of which the following is a specification.

My present invention comprehends a novel method of and apparatus for making fabric 10 such as neckties and similar articles and a novel fabric resulting from the carrying out of the steps of such method.

In fabrics as heretofore manufactured such as, for example, neckties, it has been 15 customary to dispose the weft threads at substantially right angles to the warp threads and in order to obtain a diagonal effect, it was necessary to cut the cloth, after taking it from the loom, diagonally. The 20 result of this is that after the tie has been tied a few times it becomes stretched and distorted at the neck tying portion.

In accordance with my present invention, the loom is provided with a novel construction 25 and arrangement of a reed which, during the action of weaving, disposes the weft thread at an angle to or diagonally of the warp thread so that the necktie will maintain its formation until it is worn out.

30 My invention further comprehends a novel construction of a reed and novel means for supporting it.

It further comprehends a novel construction of a narrow fabric such as, for example, 35 a necktie.

It further consists of other novel features of construction and advantage all as will be hereinafter set forth.

For the purpose of illustrating my invention, I have shown in the accompanying drawing a typical embodiment thereof which is at present preferred by me, since 40 this embodiment will be found in practice to give satisfactory and reliable results. It 45 is, however, to be understood that the various instrumentalities of which my invention consists can be variously arranged and organized and that my invention is not limited to the precise arrangement and organization of these instrumentalities as here- 50 in shown and described.

Figure 1 represents a plan view of a portion of a narrow fabric loom, embodying my invention.

55 Figure 2 represents a front elevation of the reed.

Figure 3 represents a side elevation of the reed.

Figure 4 represents a sectional plan view 60 of the reed.

Figure 5 represents a plan view of a fabric blank resulting from my method.

Similar numerals of reference indicate corresponding parts.

Referring to the drawing. 65

The construction and arrangement of narrow fabric looms is well known to those skilled in this art and I have therefore deemed it unnecessary to illustrate and describe in detail the construction and operation of a loom of this character. The loom is provided in the usual manner with the reed box 1 which carries the reed 2, the latter having the reed frame 3 and the reed 4. The reed frame 3 is connected with the reed box 1 by means of the bars 5 and 6, respectively, so that the reeds 4 are disposed parallel to the warp threads 7 so that when the reed box moves in its operative direction, the weft 8 is disposed diagonally of 70 or at an angle to the warp thread 7. In Figure 3, I have shown the fabric 9 and the lines of warps 10 and 11 which form the shed through which a bobbin or shuttle is passed so that the weft thread passes between the 75 warp threads on the line 12, as indicated in Figures 1 and 2.

The narrow fabric is provided at opposite sides with the selvage which is woven in the usual and conventional manner, and a detailed description of the manner in which the selvage is formed is therefore believed 80 to be unnecessary.

The warp threads are narrowed or contracted in the usual manner at the knot tying portion of the tie in order to reinforce 85 it. It will thus be understood that I weave a plurality of continuous flat necktie blanks and the blanks are severed transversely, after 90 which the tie is folded to bring the selvage 95 portions on the underside, and the juxtaposed edges are then secured together along the central median line of the rear of the blank. The neckband portion may be reinforced in any desired or conventional manner. 100

In Figure 5, I have shown a necktie blank 13 having the narrow portion 14 and the flaring end portion 15 and the lines 16 designate the lines showing the diagonal disposition of the weft threads, certain of which 110 may be of contrasting color or colors in ac-

cordance with the design which it is desired to produce.

In so far as I am aware, I am the first in the art to position the reed in such a manner that the weft threads will be disposed diagonally or at an angle to the lines of the warp threads.

My novel construction and arrangement of reed enables cloth or fabric to be woven with an ordinary straight warp which runs lengthwise of the fabric, and with the weft or filling disposed at any degree or angle to produce bias weaves, diagonal stripes or checks and blocks. The dents are placed in the reed at a desired angle and then fastened in the regular reed box at the desired angle. The reed moves to and fro with the lay and beats the filling up to the desired texture of the cloth on a bias or angle, which weaves a bias fabric with a straight warp. This overcomes the complication in the methods heretofore employed wherein it was first necessary to weave the cloth with straight cross bars and then cut the goods to a certain width as required on the bias, suitable for neckwear or any other cloth that requires bias stripes which latter have a tendency to pull or to wrinkle. I effect a great saving in economy as I overcome the necessity of first weaving the cloth with straight cross bars or printing bias stripes on the cloth. The bias stripes are formed in one operation and do not pull to one side or wrinkle when the cloth is stretched. The opposite ends of the cloth or fabric are cut in parallelism with the line of the weft threads, as clearly shown in Fig. 5.

While I have described my present invention as relating more particularly to narrow fabric, it is not limited to such use but may be employed to weave fabrics of any desired width.

It will now be apparent that I have devised a new and useful method of and apparatus for making fabrics and product resulting from such method, which embodies the features of advantage enumerated as desirable in the statement of the invention and the above description, and while I have, in the present instance, shown and described an embodiment thereof which will give in practice satisfactory and reliable results, it is to be understood that this embodiment is susceptible of modification in various particulars without departing from the spirit or scope of the invention or sacrificing any of its advantages.

Having thus described my invention, what I claim as new and desire to secure by Letters Patent, is:—

As a new article of manufacture a fabric for neck ties having selvage edges throughout its length said fabric having the weft threads woven diagonally with respect to the lines of warp threads and having the respective ends of the fabric cut in parallelism with the line of said weft threads, the neck band portion of the fabric being narrowed and the opposite ends thereof flaring.

CHARLES SEIDMAN.
